UNITED STATES PATENT OFFICE

EDMUND SCHMIDT, OF BERLIN-TEMPELHOF, GERMANY, ASSIGNOR TO THE FIRM
AUTOM-SPEZIAL-MASCHINEN G. M. B. H., OF BERLIN, GERMANY

APPARATUS FOR CAPPING AND PARAFFINING THE CARBON RODS OF THE DOLLIES OF
ELECTRIC DRY BATTERIES

Application filed March 29, 1929, Serial No. 351,011, and in Germany December 15, 1927.

The carbon rods of the dollies of electric dry batteries must be provided with a current-conducting metal cap which must then be coated with paraffin in order to prevent short circuits when the dollies of rods are assembled as, for example, in conveying means, and to prevent corrosion of the metal cap.

The invention relates to a machine by means of which these operations are automatically carried out, that is, the carbon rods are capped therein, conveyed to the paraffin bath, coated with paraffin therein and then delivered to a conveying apparatus.

The invention is illustrated in the accompanying drawing in which

Figure 1 is a plan of the machine,

Figure 2 is a side view from the left,

Figure 3 is a section on the line 3—3 of

Figure 1, on a larger scale,

Figure 4 is a section on the line 4—4 of Figure 3.

Figure 5 is a section through the paraffin container.

A spindle 2 is mounted on the base plate 1 of the machine and all the parts are driven thereby. The principal parts of the machine are:

A container 3 for the sorting and adjustment of the caps,

A trough 4 for the conveyance of the adjusted caps,

An intermittently rotating drum 5 for receiving and adjusting the dollies relatively to the caps, and also an apparatus for connecting the dollies with the caps,

A conveyer apparatus 6 for the removal of the capped dollies, and

An apparatus 7 for paraffining the caps.

From the spindle 2 and by means of a disc 8 and cord 9, a disc 10, carried on a spindle 11 is rotated. The spindle 11 is mounted in a support 12 (Figures 2 and 4) of the base plate 1, and a cylinder 14 which is closed by a side wall 13 is rigidly attached to this support, the cylinder being rigidly fixed to the cap container 3 by means of screws. On the spindle 11 is rigidly fitted a wheel 15, carrying pins 16 in a circle adjacent to its circumference, the diameter of the pins being

less than that of a cap 17. The pins have heads 18 and they are pressed by means of springs 19 against a ring 20 fastened in the cylinder 14, the ring having an inclined surface 21 for about one half of its circumference.

The cap container 3 has at the end facing the cylinder 14, an inclined widened part 22 to which a cylindrical projection 23 adjoins the height 24 of which projection corresponds to that of a cap. A spindle 25 independent of the spindle 11 is mounted in the front end of the said spindle 11 and carries an arm 26 which projects into the projection 23 while the other end of the spindle 11 is mounted in the container 3.

The caps are supplied into the container 3 through an opening 27 adapted to be closed and the caps slide on the inclined surface 22 into the slot formed by the projection 23. As the height of the latter is equal to the height of the caps, although this height is smaller than the diameter of the caps, the latter can pass into the slot only when their central axis is parallel to the axis of the container 3. When the wheel 15 is rotated, the pins 16 with the heads 18 move upwardly on the inclined surface 21, and are drawn back, so that they pass out of the slot 23 and caps can enter into the latter. When then the pins are successively released at the inclined surface 21, they are drawn forward by the springs 19, penetrate into one of the caps situated in the slot 23, provided the open end of the cap faces the pin, and retains the cap. It pushes in front of it in the slot 23 the caps which have not been seized by any pin, until the said caps reach a stripper 28 (Figure 3). This latter extends through the flange 29 of the cap container 3 into the slot 23 and is under the pressure of a spring 30. By means of the stripper the caps not gripped by a pin 16 are forced out of the slot 23 and fall back into the container 3. The pin, however, forces back the stripper as it passes thereunder. The stripper 28 then flies back, by means of the spring 30, into the slot 23.

The pin then brings the cap carried thereon to the conveying trough 4 (Figure 3). This consists of a channel 31 open towards the pin 100

and situated in the flange 29 and having a diameter equal to the diameter of the caps, into which it guides the cap. The inclined surface 21 then grips under the head 18 of the pin and draws it back so that the cap is freed from the pin. The caps press one another into the channel 31 and onwards into a pipe 32 connected thereto, up to a pipe leading downwards on to the dollies drum 5, in which pipe they slide down. When the pipe is filled with caps, the surplus caps pass through a branch pipe 35 into a container.

In order to prevent incorrectly positioned caps remaining at the point of the slot 23 where the pins are released from the inclined surface 21 and spring forward, an arm 26 is provided (Figure 3) to which a rocking movement is imparted from the main spindle 1 through an eccentric disc 34 and connecting rod 35, the extent of the throw being indicated in Figure 3. The caps are thus prevented from becoming fixed.

The dollies 36 to be capped (Figure 2) are placed on the dolly drum 5 either automatically or by hand. The drums are provided with recesses 37 to take the dollies 36 with recesses 38 for the carbon rods and with recesses 39 for the caps 17, and are rotated intermittently by one division at a time. The drive takes place from the main spindle 2 by means of an eccentric disc 41 and rod 42 which rotates a ratchet wheel 44 by means of a pawl 43.

In order to prevent the caps 17, as they slide out of the pipe 32 into the recesses 39, from tipping towards the carbon rod 43, a slide 45 (Figure 3) is provided which moves in a slot 46 (Figure 6) between the recesses 38 and 39 and is sufficiently long to close several recesses. The said slide is attached by one arm 48 to the drum spindle 49 of the dolly and is rocked up and down by the backward and forward swinging arm 47 of the pawl 43 of the ratchet wheel 44, so that it alternately lies in front of and away from the pipe 32.

When the drum has brought a dolly into the capping position, there is rotated from the main spindle 2 by means of bevel wheels 50, a spindle 51 on which is fitted an eccentric 52 (Figure 2) by means of which a lever 54 hinged to the plate 1 at 53, is rocked to and fro. The said lever moves a forcing rod 56 running in a straight direction in a guide 55, against the dolly 36, which is thereby forced with its carbon rod 40 into the opposite cap 17, which is held by a spring bolt 57 which allows the cap to yield in the case of excessive pressure. A spring 58 draws back the press lever 54. By means of the intermittently rotating drum 5 the capped dollies are carried to a rocking trough 59. The latter is fitted on an arm 61 pivoted at 60, with which a rod 62 engages. The latter is rocked to and fro from the main driving spindle 2 by means of

an eccentric 63, whereby the trough 59 is rocked, so that it takes a dolly from the drum 5 and passes it on the conveying apparatus 6.

For this purpose a rod 66 moved in a straight line is reciprocated, from the spindle 51 (Figure 1) by means of a crank 64 and connecting rod 65, the rod 66 bearing against the base of the dolly in the trough 59 and driving it into the conveying apparatus. The latter consists of a band passing over pulleys 67, 68. The pulley 67 is mounted on the spindle 69 which is intermittently rotated by means of a ratchet wheel 70 and pawl 71. The pawl receives its drive from the spindle 51 by means of eccentric 72 and rod 73.

To the inner side of the conveyer band 6 cylindrical containers 74 are fixed at equal distances apart which are so shaped that they can receive the dollies proper, and which have a hole 75 at their base, through which the carbon rod 40 of each dolly projects. By means of the rod 66 the dolly is thus forced into one of the containers 74 and carried by the band 6 to the paraffin apparatus 7 (Figure 5). The latter consists of a container 77, heated by a heating apparatus 76, and containing the liquid paraffin bath. Into the latter a scoop 78, projects the depth of which corresponds to the extent to which the cap and carbon rod are to be paraffined, and which is connected by means of an arm 79 with a slide 80. The latter is moved up and down by means of an angle lever 81 and rod 82 from an eccentric 83 which is rotated by the spindle 2. The scoop 78 is thus alternately raised and lowered, and when it is raised the carbon rod 40 provided with the cap dips into the mass contained in the scoop and is thereby paraffined.

The band 6 then carries forward the finished dollies. It is sufficiently long to permit the paraffin on the carbon rods to cool during the transit. The wheel 68 is rotated by the band 6. While the dollies are being carried round the said wheel they are prevented from falling out of the containers 74 by a plate 84, until they come over a conveyer apparatus 85 into which they fall and by which they are carried forward. In order to prevent a dolly adhering to a holder 74, a stripper 86 is provided which presses against the projecting carbon rod.

Brake discs 87 forced against each other by a spring 88 are provided on the spindle 49 and ensure the exact working of the said spindle. Similar brake discs 89 with spring 90 are arranged on the spindle 69.

Having now particularly described and ascertained the nature of my said invention and in what manner the same is to be performed, I declare that what I claim is:

1. In a machine for the automatic capping and paraffining of the carbon rods of the dollies of electric dry batteries, a main drive,

a container for the metal caps, a wheel-rotated from said main drive and forming with the container a slot of a width equal to the height of the caps, spring pins arranged in the said wheel, means to draw back and release the pins intermittently, so that they engage into the slot and in each of the caps contained therein, a guiding trough receiving the caps from the spring pins after withdrawal of the said pins, in front of the dollies to be capped, a press apparatus for forcing

5 the caps on to the carbon rods, a paraffin bath, means to bring the dollies capped automatically to said bath, means for dipping the heads of the carbon rods into said bath and means to remove the finished dollies.

2. In a machine for the automatic capping and paraffining of the carbon rods of the dollies of electric dry batteries, a main drive, a container for the metal caps, a wheel rotated from said main drive and forming with the container a slot of a width equal to the height of the caps, spring pins arranged in the said wheel, means to draw back and release the pins intermittently, so that they engage into the slot and in each of the caps contained therein, a guiding trough receiving the caps from the spring pins, after withdrawal of the said pins, in front of the dollies to be capped and a spring stripper arranged in front of the inlet of the guide trough and removing the caps raised in the slot but not gripped by the pins, out of the slot and throwing them back into the container.

3. In a machine for the automatic capping and paraffining of the carbon rods of the dollies of electric dry batteries, a main drive, a container for the metal caps, a wheel rotated from said main drive and forming with the container a slot of a width equal to the height of the caps, spring pins arranged in the said wheel means to draw back and release the pins intermittently, so that they engage into the slot and in each of the caps contained therein, a guiding trough receiving the caps from the spring pins, after withdrawal of the said pins, in front of the dollies to be capped, a clearing device arranged in the slot between the cap container and the wheel, a spindle for said clearing device and means to rock the spindle from the main drive.

4. In a machine for the automatic capping and paraffining of the carbon rods of the dollies of electric dry batteries, a main drive, a container for the metal caps, a wheel rotated from said main drive and forming with the container a slot of a width equal to the height of the caps, spring pins arranged in the said wheel heads on said spring pins, a fixed ring, there being an inclined surface on said ring, the said ring and the inclined surface forming a guide for the heads and a trough guiding the caps to the dollies.

5. In a machine for the automatic capping

and paraffining of the carbon rods of the dollies of electric dry batteries, a main drive, a guide trough to bring the caps to the dollies, a drum rotated intermittently from the main drive, there being recesses in said drum receiving the dollies, there being other recesses, into which the caps fall from the guide trough and which are so arranged that the caps lie centrally to the axes of the carbon rods, and means to move forward the dollies against the caps.

6. In a machine for the automatic capping and paraffining of the carbon rods of the dollies of electric dry batteries, a main drive, a guide trough to bring the caps to the dollies, a drum rotated intermittently from the main drive, there being recesses in said drum receiving the dollies, there being other recesses, into which the caps fall from the guide trough and which are so arranged that the caps lie centrally to the axes of the carbon rods, means to move forward the dollies against the caps, there being slots in the drum between the recesses for the caps and the recesses for the dollies and a slide movable in the slots and closing the opening of the guide trough.

7. In a machine for the automatic capping and paraffining of the carbon rods of the dollies of electric dry batteries, a main drive, a guide trough to bring the caps to the dollies, a drum rotated intermittently from the main drive, there being recesses in said drum receiving the dollies, there being other recesses, into which the caps fall from the guide trough and which are so arranged that the caps lie centrally to the axes of the carbon rods, means to move forward the dollies against the caps, there being slots in the drum between the recesses for the caps and the recesses for the dollies and a slide movable in the slots and closing the opening of the guide trough said slide being sufficiently wide to enable it to close each time several recesses of the drum.

8. In a machine for the automatic capping and paraffining of the carbon rods of the dollies of electric dry batteries, a main drive, a guide trough to bring the caps to the dollies, a drum rotated intermittently from the main drive there being recesses in said drum receiving the dollies, there being other recesses, into which the caps fall from the guide trough and which are so arranged that the caps lie centrally to the axes of the carbon rods, means to move forward the dollies against the caps, there being slots in the drum between the recesses for the dollies and the recesses for the caps, a slide, a double lever on the axis of the drum and means swinging the double lever and the slide intermittently.

9. In a machine for the automatic capping and paraffining of the carbon rods of the dollies of electric dry batteries, a main drive, a guide trough to bring the caps to the dollies,

a drum rotated intermittently from the main drive, there being recesses in said drum receiving the dollies, there being other recesses, into which the caps fall from the guide trough and which are so arranged that the caps lie centrally to the axes of the carbon rods, means to move forward the dollies against the caps and means to brake the rotation of the drum.

10. In a machine for the automatic capping and paraffining of the carbon rods of the dollies of electric dry batteries, a main drive, a guide trough to bring the caps to the dollies, a drum rotated intermittently from the main drive, there being recesses in said drum receiving the dollies, there being other recesses, into which the caps fall from the guide trough and which are so arranged that the caps lie centrally to the axes of the carbon rods, means to move forward the dollies against the caps, 20 and a spring bolt holding the caps during the insertion of the carbon rods yieldingly.

11. In a machine for the automatic capping and paraffining of the carbon rods of the dollies of electric dry batteries, a main drive, a guide trough to bring the caps to the dollies, a drum rotated intermittently from the main drive there being recesses in said drum receiving the dollies, there being other recesses, into which the caps fall from the guide trough and which are so arranged that the caps lie centrally to the axes of the carbon rods, means to move forward the dollies against the caps, a tiltable trough, means to move the dollies into the said trough, means driven by the main drive to tilt the trough, a conveyer apparatus receiving the dollies from the trough and bringing them to a paraffin bath.

12. In a machine for the automatic capping and paraffining of the carbon rods of the dollies of electric dry batteries, a main drive, a guide trough to bring the caps to the dollies, a drum rotated intermittently from the main drive and bringing the dollies to the caps, means to unite the dollies with the caps, a circulating band having containers corresponding to the dollies and means to bring the dollies from the drum into the said containers.

13. In a machine for the automatic capping and paraffining of the carbon rods of the dollies of electric dry batteries, a main drive, a guide trough to bring the caps to the dollies, a drum rotated intermittently from the main drive and bringing the dollies to the caps, means to unite the dollies with the caps, a circulating band having containers corresponding to the dollies there being a hole at the base of the said containers through which the carbon rod of the dolly can project, and means to bring the dollies from the drum into the said containers.

14. In a machine for the automatic capping and paraffining of the carbon rods of the dollies of electric dry batteries, a main

drive, a guide trough to bring the caps to the dollies, a drum rotated intermittently from the main drive and bringing the dollies to the caps, means to unite the dollies with the caps, a circulating band having containers corresponding to the dollies, there being a hole at the base of the said containers through which the carbon rod of the dolly can project, means to bring the dollies from the drum into the said containers, a paraffining apparatus arranged between the two stretches of the band and means to coat the carbon rods with paraffin.

15. In a machine for the automatic capping and paraffining of the carbon rods of the dollies of electric dry batteries, a main drive, a guide trough to bring the caps to the dollies, a drum rotated intermittently from the main drive and bringing the dollies to the caps, means to unite the dollies with the caps, a circulating band having containers corresponding to the dollies there being a hole at the base of the said containers through which the carbon rod of the dolly can project, means to bring the dollies from the drum into the said containers, a paraffining apparatus arranged at one end of the band between the two stretches of the same, means to coat the carbon rods with paraffin, the band being sufficiently long that the carbon rods after coating with the paraffin can cool during the further transport.

16. In a machine for the automatic capping and paraffining of the carbon rods of the dollies of electric dry batteries, a main drive, a guide trough to bring the caps to the dollies, a drum rotated intermittently from the main drive and bringing the dollies to the caps, means to unite the dollies with the caps, a circulating band having containers corresponding to the dollies there being a hole at the base of said containers through which the carbon rod of the dolly can project, means to bring the dollies from the drum into the said containers, a paraffining apparatus arranged between the two stretches of the band, a scoop arranged in the paraffining apparatus and means driven by the main drive and moving the scoop up and down in the paraffining apparatus, so that when the scoop is raised the carbon rods dip therein.

In testimony whereof I affix my signature.

EDMUND SCHMIDT.
